UNITED STATES PATENT OFFICE

XOROL R. OLIVER, OF OAKLAND, CALIFORNIA

CHAIR FOR PRACTICING ELECTROLYSIS

Application filed June 21, 1928. Serial No. 287,300.

This invention relates to surgical chairs and particularly to chairs designed to be used in the operation of electrolysis, that is the removal of superfluous hair.

5 The chairs ordinarily used by practitioners of electrolysis comprise a seat and an adjustable back made up of a plurality of sections adjustable with reference to each other so that the back may be inclined with relation 10 to the seat and the sections of the back be independently adjustable. The chair, however, is not properly adjustable for long or short patients for the reason that when the back is inclined at an acute angle, which is 15 the proper position for operating and the most comfortable position for the patient, the seat if moved upward separates from the back and leaves a gap which has to be filled in with cushions, if filled in at all, and if the 20 seat is not raised vertically, then the chair is too long for short patients.

A further difficulty in chairs of this character is that the side of the back and the side 25 of the seat constitute a straight line and the practitioner, in order to operate, must flex her back and shoulders in order to lean over a patient while sitting beside the chair and not only is this an extremely uncomfortable and tiring position for the operator, but the 30 straight edge of the back and the seat bears against the hip of the operator, and this pressure also soon becomes very uncomfortable.

The constant practicing of this profession 35 with a chair of this character tends to twist the practitioner to some extent, giving a permanent flex to the spine and tends to cause one shoulder to be permanently raised with relation to the other shoulder.

40 Another difficulty with chairs of this character is that the arms are not transversely adjustable and as a consequence the patient cannot move the arms into a natural position across the body, but must always hold the arms at right angles to the body, a position which is not natural and is very tiring. Inasmuch as a patient undergoing the operation 45 of electrolysis must lie as quiet as possible and move as little as possible it follows that anything which would tend to render the patient more comfortable tends to make the

operation more successful. The slightest movement on the part of the patient tends to withdraw the depilating needles from the tissue and these must be replaced by the operator and the operator must constantly be on 55 the lookout for any strain exerted on the electric cords carrying the depilating needles and shift these cords to take off this strain and prevent the pulling out of the needles as explained in my copending application Serial 60 No. 287,299 filed June 21, 1928, on an electric depilator.

One of the objects of this present invention is to provide, in connection with an operating chair having an angularly adjustable back 65 formed of independently adjustable sections, a seat which is movable independently of the back or any adjustment thereof.

Another object is to so arrange the seat that as the seat moves upward it will swing 70 rearward, thus as the seat is adjusted for a relatively short person, the seat will automatically close any gap between the seat and the back.

Another object is to so form the back and 75 seat adjacent their junction as to accommodate the body of the operator so that the operator may sit in close to the patient and operate without strain or fatigue, and another object is to so construct the arms of 80 the chair that they may be swung into a position where they will support the arms of the patient when the latter are in their normal and easy position.

85 My invention is illustrated in the accompanying drawings wherein—

Fig. 1 is a side elevation showing a chair constructed in accordance with my invention, the chair being stripped of unessential features to show the principle of the device. 90

Fig. 2 is a top plan view of the construction shown in Fig. 1;

Fig. 3 is an enlarged view of the means 95 illustrated for adjusting the back;

Fig. 4 is an enlarged top plan view showing the means illustrated for adjusting the sections of the back relative to each other; and

Fig. 5 is a fragmentary elevation of the 100

seat of the chair showing one of the adjustable arms.

It is to be understood that in the drawings herewith, I have merely illustrated the essential features of an operating chair and that the actual construction may be modified and changed in many ways without departing from the principle shown in these drawings.

In the drawings the back 10 is formed with a plurality of sections designated respectively 11, 12 and 13. The section 11 is for the support of the lower portion of the back, the section 12 for the support of the upper portion of the back, and the section 13 acting as a head rest. The sections 11, 12 and 13 are illustrated as being supported by irons 15, and as shown in Fig. 4 these irons are overlapped and their confronting faces are radially toothed or corrugated as at 16. These faces are held in close engagement with each other by an adjusting screw 17 having any desired form and when this screw is tightened the overlapping faces of the sections are held in locked engagement with each other and when loosened, one section may be adjusted upon the other. The lower ends of the irons 15 of the section 11 are pivotally mounted upon any suitable supporting members shown diagrammatically in Fig. 1 and designated 18, and any suitable means may be used for holding this lower section in angular relation to the seat, such as the sector-shaped rack or ratchet 19 having teeth 20 and coacting with a locking pawl 21 having a handle 22 and held against the teeth by a spring 23.

It is obvious that with this mechanism the back may at any time be raised and may be held in this position by the locking pawl 21 and that by releasing the locking pawl the back may be lowered. It is again reiterated that any other suitable mechanism may be used for securing the adjustment of the back and its sections and that my invention does not lie in any peculiar means for this purpose, but in the combination of such an adjustable back with the seat now to be described.

The seat 24 is shown as pivotally connected to supporting links 25 which are pivoted at their lower ends to any supporting base or plate 26. Obviously with this construction, as these supporting links or legs are swung forward the seat will be swung rearward toward the back, and thus as the back is moved into a properly inclined position the seat may be caused to follow the back. I do not wish to be limited to any particular means for raising or lowering the seat, but preferably use pneumatic means for this purpose and have illustrated therefore a cylinder 27 having therein a piston 28 whose piston rod is engaged with any suitable portion of the seat, but as shown is engaged with a bar 29 connected to the legs 25. The pump 30 is designed to be disposed in any convenient

relation to the chair and to be operated by a handle 30. Inasmuch as this means for raising or lowering the chair is old and well known by itself, I have not illustrated it in detail, but only diagrammatically.

The seat 24 is provided with a foot-rest 31 mounted upon supporting bars 32 which are operatively engaged with the underside of the seat for sliding movement either forward or rearward to adjust it to the foot-rest. The seat is likewise provided with the arm rests 33. These, as illustrated, are mounted upon vertical posts 34 extending upward from the seat, so that the arm rests will move upward with the seat, or downward therewith. The arm rests 33 are rotatably mounted upon the upper ends of the posts 34 so that the arm rests may be swung to the position shown in dotted lines in Fig. 2 or into a position shown at right angles to the back of the seat as desired.

For the purpose of permitting the operator to assume a correct position with relation to the patient as before explained the back section 11 is cut away at 35 to any desired depth and with any desired degree of curvature and the seat 24 is likewise cut away at 36, the edge of this cut away portion being preferably slightly convexly rounded. Thus the practitioner will not be impeded in her work, she will not have to have to flex her body in order to properly operate nor will her hip bear constantly against the seat, as is the case where the side edge of the seat extends parallel to the length of the back.

While I have illustrated certain details of construction it is to be understood, as before stated, that these might be modified in many ways without departing from the spirit of the invention as defined in the appended claims.

I claim—

1. A chair of the character described including a back and a seat, the back being pivotally mounted at its lower end for angular adjustment and being composed of sections, each section being adjustable into angular relation to the next adjacent section, the seat being independent of the back and mounted for vertical and rearward movement or vertical and downward movement, and manually operable means for adjusting the seat to a plurality of positions and holding it in its adjusted position.

2. A chair of the character described comprising a base, a back operatively supported upon the base for tilting movement, a seat operatively supported upon the base for rearward and forward movement and simultaneous movement in a vertical plane, the seat being independently adjustable with relation to the back, the seat and back at their junction being cut away on one side to accommodate the body of an operator.

3. A chair of the character described, including a back and a seat, the back being pivotally mounted for angular adjustment and being composed of sections each angularly adjustable with relation to adjacent sections, the seat being independent of the back and mounted for vertical and forward movement whereby the seat may be shifted toward the back as the seat is raised, manually operable means for adjusting the seat into a plurality of positions and holding it in its adjustable positions, and arm rests mounted upon the seat and moving therewith, the arm rests being mounted for swinging movement in a horizontal plane.

In testimony whereof I hereunto affix my signature.
